(57) CLAIM

The ornamental design for a form for displaying or fitting, as shown and described.

DESCRIPTION

FIG. 1 is a front perspective view of a form for displaying or fitting showing the new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a rear perspective view thereof.

FIG. 9 is a front perspective view showing a form for displaying or fitting, shown in an alternate embodiment with waist and ankle extensions;

FIG. 10 is a front view thereof;

FIG. 11 is a rear view thereof;

FIG. 12 is a right side view thereof;

FIG. 13 is a left side view thereof;

FIG. 14 is a top view thereof;

FIG. 15 is a bottom view thereof; and,

FIG. 16 is a rear perspective view thereof.

The broken lines showing the rod and leg openings shows unclaimed subject matter for the design and forms no part thereof.

1 Claim, 8 Drawing Sheets
